DRAWING FILE

Harold E. Smith, Adrian, Mich.

Application October 13, 1938, Serial No. 234,815

2 Claims.

(Cl. 45—7)

This invention relates to drawer cabinets especially for receiving sheets of tracings and prints therefrom of usual working drawing dimensions.

5 This invention has utility when incorporated in section units of flat holding capacity as closed against dust accumulation.

Referring to the drawing:

Fig. 1 is a front view, with parts broken away, 10 of an embodiment of the invention in a drawer filing cabinet;

Fig. 2 is a fragmentary plan view of a drawer partially withdrawn from a section;

Fig. 3 is a section on the line III—III, Fig. 2, 15 showing the drawer in its register position in the cabinet section;

Fig. 4 is a fragmentary view on a reduced scale of a sheet-retaining rear overhang for the drawer.

20 Upright members or legs 1 may mount bottom member or base 2 as a support. On this support may be placed cabinet members or sections 3 in building up the sections to form a unit. These cabinet sections may be stacked in upright vertical series and surmounted by a top member or cap section 4. These sections 3 adjacent their forward or front ends have projecting dowel members or tapered pins 5 on their lower or under sides. On their top or upper sides there are, 25 in complementary location, recesses, openings or sockets 6 into which the tapered termini of the pins from the bottom of the next upper or higher section thereover may slide in bringing the sections into registry for assembling them into a vertical series of the stack. The sections 3 are thus directly superposed and laterally aligned as to their vertical upright sides, back and front.

These sections 3 have therealong, from adjacent the pins 5, metal strips as supporting means or guides in completing the way. These guides extend from the front opening 8 toward the back or rear 9. The front port or opening 8 at its upper side has front frame portion 10. From this frame portion 10 sheet portion 11 of press board or veneer may extend rearwardly. The rear portion or back of the section 9 has groove or undercut 12 adapted to receive tongue 13 of the companion or adjacent section as the pins come into register in the sockets 6. The section 30 or unit as thus assembled provides a pocket or receiver for a slide member or drawer. This drawer has bottom 14, rear or back 15, and front 16, with parallel sides 17 between the front and back and as adjacent the bottom.

The upper side of the pocket or receiver is flat or flush as to the top of the drawer. The drawer has from its rear portion a forwardly ex-

tending overhang of strips or flap sections 20 in thereby providing an efficient holding means to retain sheets, say of tracings, prints, drawings, and the like. The free edges 20, ride against the under side of the portions 11, 10, in drawer shifting.

The drawer back has inclined seat or beveled off portion 22. In this seat 22 is located fastening means effective to anchor or hold the overhang 10 with the drawer, so that the free edge 10 20 of this overhang may be an effective wiper or slip means against the under side of the top 10, 11, whether the drawer travel be inward or outward for full transit either way. This material for the overhang may be a normal yieldable flat 15 sheet stock adapted to hold its shape, such as Celluloid or paper. When these strips 20 are adopted, they may have their free ends directed in proximity to the under side 10, 11, of the top of the pocket or way for the drawer. Such directing effectiveness may be supplemented through the additional holding action attained by locating between the strips 20 and relatively flush therewith, intermediate additional strip means 24, say of paper or cardboard anchored by adhesive or tacks with the top of the port at the upper 25 side of the drawer. These additional strips are substantially flush with the free ends of the tongues or strips 20.

What is claimed and it is desired to secure by 30 United States Letters Patent is:

1. A cabinet having a drawer receiver entrance port having a top extending therefrom, and a drawer having a rear provided with forwardly and upwardly inclined seat means, spaced overhanging strips anchored with the seat means and directed thereby into flush proximity with the under side of said top, said under side having fixed therewith additional strip means between the strips to provide channelways for the strips, 35 said overhanging means having the free terminus portions thereof normally self-flexing to ride in said ways and coacting for fully clear uninterrupted entrance and exit of the drawer as to the entrance port.

2. A cabinet having a drawer receiver entrance port having a top extending therefrom, and a drawer for said port having a rear provided with forwardly and upwardly inclined seat means at its upper edge portion, and independent spaced 50 flexible strips anchored with the seat means and directed forwardly and upwardly by said seat means to be normally flexed in riding against the under side of said top as the drawer is shifted into and outward as to the entrance port.

HAROLD E. SMITH.
